UNITED STATES PATENT OFFICE.

JOSEPH BERG, OF CHICAGO, ILLINOIS, ASSIGNOR TO STEWART-WARNER SPEEDOMETER CORPORATION, OF CHICAGO, ILLINOIS, A CORPORATION OF VIRGINIA.

SUPPORT FOR LIGHT-DIFFUSERS.

1,281,485.

Specification of Letters Patent.

Patented Oct. 15, 1918.

Application filed December 22, 1917. Serial No. 208,422.

To all whom it may concern:

Be it known that I, JOSEPH BERG, a citizen of the United States, residing at Chicago, in the county of Cook and the State of Illinois, have invented certain new and useful Improvements in Supports for Light-Diffusers, of which the following is a specification, reference being had to the accompanying drawings, forming a part thereof.

10 The purpose of this invention is to provide a simple and economical support for a light diffusing globe of the type more fully described in detail in my pending application, Serial #192,639. It consists in the 15 features and elements of construction and their combination hereinafter described and shown in the drawings as indicated by the claim.

In the drawings:

20 Figure 1 is a vertical axial section showing a supporting device embodying this invention associated with an incandescent lamp bulb and a diffusing globe in position of use.

25 Fig. 2 is a front elevation of such a support including a fragment of the diffusing globe.

Fig. 3 is a transverse section of the supporting device as it appears before the globe 30 is attached.

35 Fig. 4 is a detail view showing a fragment of the supporting device to illustrate more clearly the non-abrasive pad of the sort carried on each of its radial arms.

It may be understood that the diffusing globe, A, is intended for use in vehicle headlights for screening the reflector indicated in dotted lines at B, from any direct rays from the lamp filament, C, permitting only 40 diffused light to reach the reflector from said lamp, so that the reflector will emit a brilliant glow of light rather than a concentrated beam. The globe, A, is preferably of glass and therefore of considerable 45 weight and must be supported either upon the stem, D, of the lamp bulb, E, or upon the projecting end of the socket tube, F, which carries said bulb, E, and to prevent injury to such part, it is important to prevent 50 vibration of the globe, A.

The fitting which is the subject of this

invention is therefore made rearwardly convex in form following approximately the curvature of the reflector, B, and includes a number of radially extending arms, 1, each 55 carrying a non-abrasive pad, 2, facing rearwardly for contact with the surface of the reflector, B. At the center the fitting is apertured at 3 to accommodate the lamp stem, D, or if necessary the socket tube, F, 60 and around this aperture, 3, is secured the base coil of a conically helical or spiral spring, 4, whose smallest and forward coil is large enough to admit the lamp stem, D, as indicated in Fig. 1. Thus it will be seen 65 that upon insertion of the lamp stem, D, through the small coil of the spring, 4, and locking of the lamp in the socket tube, F, by engagement of its locking pin, G, in bayonet slots (not shown) in the tube, F, in a well 70 understood manner, the spring, 4, is longitudinally compressed and serves to transmit a yielding pressure to the fitting disposed with the pads, 2, against the reflector surface, B. The pads, 2, are sufficient in number and area so that their frictional engagement with said surface of the reflector, B, under the pressure of the spring, 4, is sufficient to effectually check any serious vibration involving slippage of the pads, 2, upon the 80 reflector, B, and the pressure of the spring, 4, is sufficient to prevent the padded arms, 1, from being jarred out of contact with the reflector, B, by any ordinary road shock incident to travel of the vehicle. 85

In the form shown, the fitting may be made as a die casting, having a composition which includes a considerable portion of tin, so that for securing the base coil of the spring, 4, the thin flange, 5, may be merely 90 bent over the wire of the coil, and similarly for securing the globe, A, in position, the rim or flange, 6, may be spun down against the glass rim of its central opening as shown in Fig. 1, thus providing a very simple and 95 economical assembly of the parts.

I claim:

A fitting for the purpose indicated comprising a rearwardly convex centrally apertured member having a plurality of radial arms, each carrying a non-abrasive pad on its rear surface, and a forwardly projecting

flange concentric with the central aperture adapted to be clamped down upon the material of the object to be supported by the fitting, such object being apertured to fit over and encompass said flange; together with lugs projected forwardly within the area bounded by said flange and bendable

toward the latter for retaining the base coil of a spring substantially as described.

In testimony whereof I have hereunto set my hand at Chicago, Illinois, this 30th day of November, 1917.

JOSEPH BERG.
